UNITED STATES PATENT OFFICE.

SMITH L. STOVALL, OF KERTO, CALIFORNIA, ASSIGNOR TO C. A. GIBSON AND J. F. GIBSON, JR., BOTH OF VISALIA, CALIFORNIA.

METHOD OF AND TANK FOR STORING OIL.

Application filed January 4, 1921. Serial No. 435,013.

To all whom it may concern:

Be it known that I, SMITH L. STOVALL, a citizen of the United States, and a resident of Kerto, Kern County, State of California, 5 have invented a certain new and useful Method of and Tank for Storing Oil, of which the following is a specification.

The invention relates to tanks for storing or containing crude oil or oil products.

10 At the present time it is the practice to store crude oil and oil products in tanks, which are provided with roofs, preferably steel roofs, which are gas tight and which are secured to the sides of the tank in a gas 15 tight manner. These tanks are vented to preclude the accumulation of pressure in the tank due to the introduction of oil into the tank or the evaporation of the oil or the lighter constituents thereof in the tank. 20 The vent usually consists of a pipe of large diameter secured to the tank adjacent the top, extending downward to the ground and led off some 75 feet from the tank, where its open end is covered with several thicknesses 25 of fine wire gauze. As the oil in the tank evaporates or volatilizes, the gas produced passes out through the pipe, and the space in the tank above the oil is filled with pure gas, which is not explosive. When oil is 30 drawn from the tank, however, or when the atmospheric temperature falls, air is drawn into the tank through the vent pipe, producing an ideal explosive mixture therein, which is a serious fire hazard, since the explosive 35 mixture may be readily ignited by a static discharge or by other influences. It is essential that the vent pipe be left open, otherwise the withdrawal of the oil or the condensation of the gas due to temperature 40 drop, would cause a condition of vacuum which would cause the tank to collapse.

An object of my invention is to provide an oil storage tank in which this fire and explosion hazard is practically eliminated.

45 At practically all ordinary atmospheric temperatures, there is a large amount of evaporation or volatilization of the lighter constituents of the oil and the research departments of the United States Government have estimated that the loss due to evaporation of the oils in storage alone, in the United States, is in excess of \$125,000,000 per year. The investigations of the research 50 departments have been carried on almost entirely with reference to the large storage

tanks, and as far as I am aware, no investigations have been made to determine the losses due to evaporation and volatilization of the oils before they reach these large storage tanks. The custom in the oil fields is to 60 flow the oil from the well through a flume, in which much of the sand is settled out, then into a large tank wherein water and more sand is settled out and then into a gauging tank where it is held for a day. 65 These two tanks are known as flow tanks, and the loss of the lighter constituents of the oils in these tanks by evaporation or volatilization, is very great. The lighter constituents lost by evaporation or volatilization 70 are of very high gravity, probably around 80° Baumé, and comprise the more valuable constituents of the oil.

Another object of my invention is to greatly reduce the amount of the lighter 75 constituents of the oil which are lost by evaporation or volatilization.

The invention possesses other advantageous features, some of which, with the foregoing, will be set forth at length in the following description, where I shall outline in full, that form of the invention which I have selected for illustration in the drawings accompanying and forming part of the present specification. In said drawings, I 85 have shown one embodiment of my invention, but it is to be understood that I do not limit myself to such form, since the invention as set forth in the claim, may be embodied in a plurality of forms. 90

Referring to said drawings:

Figure 1 is a vertical section through an oil tank embodying my invention.

Figure 2 is a detail of a portion of the roof structure on a larger scale. 95

In accordance with my invention, I reduce the accumulation of gas in the storage tank and conserve the gas produced, so that the loss by evaporation or volatilization is minimized; I prevent the mixture of air with the 100 gas, so that an explosive mixture is not produced and I greatly reduce the exposed area of the oil, making fire very easy to combat. The invention is applicable to tanks of any size from small tanks up to the largest storage tanks, which at the present time are usually of 55,000 barrel capacity. 105

In accordance with my invention, the tank is provided with a horizontal vertically movable partition or roof 2 which floats on the 110

- oil in the tank and raises and lowers with the oil in the tank. The partition is impervious and is preferably made of sheet metal and is of substantially the same area 5 and shape as the tank, so that only a small annular opening is provided between the partition and the side wall 3 of the tank. The partition is suitably braced, so that it will retain its shape. The buoyant partition 10 2 is formed with a depending circumferential flange 4, which forms a chamber 5 below the partition in which the liberated gases accumulate, and with an upstanding circumferential flange 6 which renders the partition buoyant when there is no accumulation 15 of gas in the chamber 5, in which instance the level of the oil is above the horizontal partition, but not above the upper edge of the flange 6. In practice, the flanges 4 and 6 are preferably integral, consisting of a sheet of metal secured intermediate its edges to the partition. When desired, the chamber within the upper flange and above the partition may be filled with 20 water to a depth of several inches, to act as a heat insulator against abrupt changes in atmospheric temperature.

Means may be provided for discharging the accumulated gases from the chamber 5, 30 when a predetermined accumulation forms therein. For this purpose, the partition is provided with a discharge pipe 8 to which is secured a flexible conduit 9, through which the gas is conveyed to a permanent conduit for further disposal, such as conveyance to a cooling or condensing plant. The discharge of gas through the pipe is controlled by a valve 12, which is controlled by variation in the accumulation of gas in the chamber. Connected to the valve 12 is a float 13, which operates to open the valve when the distance between the partition and the oil

level in the chamber reaches a predetermined maximum. The valve shown is of the sliding gate type, but it is to be understood that 45 any suitable type of valve may be used for this purpose.

The tank may be provided with a fixed roof 14, when desired, to prevent rain from entering the tank, and this roof is preferably spaced from the sides of the tank or is adequately ventilated to prevent the accumulation of any leakage gas therein.

By providing a floating or buoyant roof or partition, which floats on the surface of 55 the oil, the explosion and fire hazard is greatly reduced because no explosive mixture is produced, since no air is admitted to the tank. The gas thus remains pure and can be compressed or condensed to produce a 60 very high gravity product which may be mixed with gasoline to improve its quality. The enormous losses of this high gravity constituent are also reduced to a minimum. The oil is introduced into and withdrawn 65 from the tank through a conduit or conduits placed below the partition and preferably adjacent or in the bottom of the tank.

I claim:

The combination with a tank for containing oil or oil products, of a vertically movable partition in said tank, a depending peripheral wall on said partition forming a chamber below the partition for the accumulation of gas, a gas discharge conduit on 75 said partition, a valve for controlling the flow of gas through said conduit and means operative by variation in the amount of gas in said chamber, for opening and closing said valve.

In testimony whereof, I have hereunto set my hand.

SMITH L. STOVALL.
